UNITED STATES PATENT OFFICE

SAMUEL SEGAL, OF NEW YORK, N. Y., ASSIGNOR TO SEGAL LOCK & HARDWARE COMPANY, INC., OF NEW YORK, N. Y., A CORPORATION OF NEW YORK

ROTARY BOLT LOCK

Application filed October 23, 1925. Serial No. 65,513.

This invention relates to an improved type of rotary bolt lock.

It is an object of the invention to provide an improved device of this character which may be forced or jimmied only with extreme difficulty, but which may be readily operated over long periods of time with freedom from mechanical difficulty.

It is an additional object to provide a device which will efficiently perform the purposes for which it is intended, and which will also be economically and readily manufactured and easily assembled.

Other objects of the invention will in part be obvious and will in part appear hereinafter.

The invention accordingly comprises the features of construction, combination of elements and arrangement of parts which will be exemplified in the construction herein-after set forth, and the scope of the application of which will be indicated in the claims.

For a fuller understanding of the nature and objects of the invention reference should be had to the following detailed description taken in connection with the accompanying drawings, in which:

Figure 1 is a side elevation of one form of lock embodying the improved construction of the present invention, certain portions of the case being broken away and the mechanism being shown in retracted position;

Fig. 2 is a front view of the lock as shown in Fig. 1;

Fig. 3 is a view similar to Fig. 1, but showing certain of the parts in section and with the bolt partially projected;

Fig. 4 is a view similar to Fig. 3 and showing the bolt completely projected;

Fig. 5 is a view corresponding to Fig. 2, but showing the parts in the position which they have assumed in Fig. 4;

Fig. 6 is a sectional view taken on the lines 6—6 and in the direction of the arrows in Fig. 1;

Fig. 7 is a view similar to Fig. 1, but showing a slightly different form of lock;

Fig. 8 illustrates this latter form of lock with the bolts thereof projected;

Fig. 9 is a front view of this lock as shown

in Fig. 7 (the position which the parts assume when thrown being indicated in dotted lines); and

Fig. 10 is a sectional view taken on the lines 10—10 and in the direction of the arrows indicated in Fig. 8.

In these several views the numeral 15 indicates the lock casing, which may be of any desirable shape and material. Mounted to extend within this casing is a shaft 16, to which a crank arm 17 is attached, the movements of which are limited preferably by means of a stop 18, which may form an integral part of the casing and extend from the inner face thereof.

Within each casing a pair of spaced tracks or guides 19 are provided, these guides preferably forming a part of the case casting, and a carriage 20 is slidably mounted between these tracks. For a purpose herein-after brought out, these tracks preferably terminate at a point short of the inner and forward face of the casing, so that spaces 19' are provided at these points.

In order to effect a projection and retraction of this carriage a link 21 has its ends pivotally secured, one to the carriage, and the other to the end of the crank arm 17. Thus, as has been clearly shown in Figs. 1, 3, 4, 7 and 8, the shaft 16 may be turned in order to effect the desired carriage movements.

In the form of lock shown in Figs. 1 to 6 a dead-bolt 22 provides one of the locking elements, and this bolt may ride to a limited extent upon the tracks 19 and is in line with an opening in the front edge of the casing 15. The bolt body is formed in the described exemplification with two bores, and a pair of tubes 23 are mounted one within each of these bores, the outer ends of these tubes terminating in enlarged and oblong head-portions 24 lying beyond the outer edge of the bolt body, the inner ends of the tubes extending beyond the inner edge thereof.

In order to actuate the bolts provided by the head-portions of these tubes, the carriage 20 carries in the present instance a pair of pins 25, which are formed with spirally-extending and parallel grooves 26. These pins, in the position of the parts shown

in Figs. 1 and 2, have their inner ends within the tubes, and the latter are each provided with a screw 27 or other suitable element extending into the grooves 26. Furthermore, one of the tubes is formed adjacent its rear end with a projection 28, the second of the tubes being formed with a similar projection 29, and in the position of the parts referred to the former projection lies adjacent the inner edge of the uppermost track 19, while the latter projection lies adjacent the outer face of the lower track member.

It will be appreciated that in this form of lock, with the parts disposed as shown in Figs. 1 and 2, if the shaft 16 is turned by means of the knob attached thereto the crank 17 will be correspondingly moved and the carriage 20 will be projected along the tracks 19. At this time it will be noted that the lock, in addition to being knob-operated, may be key-actuated in any desirable manner. Such projection of the carriage 20 will obviously result in the forward edge of the dead-bolt being projected to a point beyond the casing, as in Fig. 3, and entering a keeper (not shown). During such projection the bolts provided by the enlarged heads 24 will not turn with respect to the dead-bolt, due to the fact that the turning tendency exerted thereon by means of the spiral grooves 26 and the screws 27 will be prevented, incident to the engagement of the projections 28 and 29 with the tracks, as in Fig. 6. However, upon the bolts reaching the position shown in Fig. 3 it will be apparent that the projections 28 and 29 will engage the inner face of the casing, and, as a consequence, a further projection of the bolts will be prevented. However, the carriage 20 will continue to move forward, and, as a consequence, the pins 25 will be projected within the tubes 23 so that the grooves 26 of the former will act through the screws to turn the tubes. Such turning will be allowed in this position of the parts due to the fact that the projections are now in line with the spaces 19' and are thus not restrained against movement. As a result, the heads 24 will swing to a position such as has been shown in Fig. 5, and if the keeper is formed with an inwardly-extending lip it will be understood that, in addition to the lock provided by the dead-bolt, the heads 24 will act to prevent any forcible retraction of the bolt.

Referring to the second form of lock shown in Figs. 7 to 10 inclusive, it will be observed that the carriage 30 carries pins 31 formed with spiral grooves 32, which grooves, contrary to the grooves 26, are disposed in opposed relationship, and these pins extend into the rear ends of tubes 33. The tubes are formed with enlarged heads 34 and do not, in the present exemplification, form a part of a separate dead-lock-bolt. Projections 35 extend from the tube bodies adjacent the rear

edges thereof and are adapted to ride one against each of the side faces of the tracks 19; and it will finally be noted that in this form of lock the tubes carry elements as, for example, screws 36, which enter the grooves 32.

In operation, upon the carriage being projected by means of a key mechanism, or through the medium of a hand knob, the pins will force the bolts outwardly beyond the forward edge of the casing. During such movement the bolts will not turn, incident to the fact that the projections engage the tracks. The outward movement of the bolts is limited, as in the preceding form of lock, by the projections 35 coming in contact with the front inner face of the lock casing, whereupon—and by virtue of the fact that these projections are in line with the spaces 19'—the tubes may rotate so that the enlarged heads thereof assume a position such as has been shown in Fig. 9. Thus, the bolt shanks in this case act as a dead-lock, and the enlarged heads thereof prevent their forcible retraction from the keeper.

In assembling this type of lock it will be noted that if the element 36 forms an integral part of the tube, or if desired for some reason, the grooves 32 may—as in Fig. 7—be continued beyond the forward edges of the pins so that the element 36 may properly slip into the groove upon the tube being slipped around the pin.

In both the illustrated forms of lock it will be understood that a retraction of the bolts is effected by simply retracting the carriage. During the initial stages of such retraction the projections which are associated with the tubes will engage the forward edges of the tracks 19, and as a result of the spiral grooves 26 the tubes will turn until the projections clear the tracks. Thereupon the bolts will be bodily retracted.

Thus, among others, the objects specifically aforementioned are accomplished, and since certain changes may be made in the above construction, and different embodiments of the invention could be made, without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A lock, including a pair of members arranged one behind the other and having their

- adjacent ends telescopically disposed, one of said members providing a bolt, a head secured to the outer end thereof, actuating means connected with the other of said members for 5 projecting both of the same, one of said members having one of its faces formed with a spirally-extending groove, a projection extending from the second of said members and lying within the groove, means for limiting 10 the projection of the bolt member, and means for preventing a turning thereof during certain of its stages of projection.
2. A lock, including a tube providing a bolt, a head secured to the outer end thereof, 15 a rod arranged beyond the rear of said tube and having its outer end telescopically disposed within the bore of the same, said rod corresponding in cross section to the tube, means forming a part of said tube and rod 20 resulting in a rotation of said bolt when said rod is axially moved with respect to said tube, means for axially moving said rod, means for limiting the axial movement of the tube, and means for preventing a turning thereof during 25 certain stages of its axial movement.
3. A lock, including a tube having a substantially cylindrical bore and providing a bolt, a head secured to the outer end thereof, a substantially round rod arranged to the rear 30 of said tube and having its outer end telescopically disposed within the tube bore, said rod having a spirally-extending groove formed in its face, a pin carried by said tube and riding within said groove, means for axially moving said rod, means for limiting the axial movement of said tube, and means for preventing rotation of said tube during 35 certain of its stages of axial movement.
4. A lock, including, in combination, two pairs of telescoping members, one of the members of each pair providing a bolt, a head at the outer ends of each of said members, means connected with the other of the members for projecting both of the same, one of 40 the members of each pair being formed with a spirally-extending groove, a projection extending from the second of the members of each pair and lying within the grooves, means for limiting the projection of the bolt members, means for preventing a turning thereof during 45 certain of their stages of projection, and means connecting both pairs of members to act in synchronism.
5. A lock, including a case, a dead-bolt 50 movable to extend beyond said case, a tube rotatably mounted within the bore formed in said dead-bolt, a head at the outer end of said tube and beyond the forward edge of said bolt, means movable axially within the tube bore for turning the same, means for projecting and retracting said last-named means, means for limiting the projection of said bolt and tube, and means acting during certain 55 stages of the projection of said bolt to prevent a turning thereof.
6. A lock, including, in combination, a case, a dead-bolt movable to extend beyond said case, a tube rotatably mounted within a bore formed in said dead-bolt, a head secured to the outer end of said tube and beyond the forward edge of said bolt, the inner end of said tube extending beyond the rear edge of said bolt, means carried by such rear end and cooperating with the lock case to limit the projection of said bolt and tube, means 60 associated with said tube for projecting the latter and said dead-bolt and for turning said tube, and means operating during certain of the stages of projection of said tube for preventing such turning.
7. A lock including a casing, track portions forming a part of said casing, a carriage slidably disposed upon said portions, means connected to the carriage for shifting the same, a rod member, a tube member, said 65 members being arranged one behind the other and having their adjacent ends telescopically disposed, a head secured to the outer end of the outermost member, the inner end of the innermost member being secured to said carriage, a groove formed in one of said members and a projecting part associated with the other of said members and extending into said groove to cause a relative turning of said members and means preventing, under certain 70 stages of projection of the members, such turning.
8. A lock including a casing formed with track portions, a carriage slidably mounted upon said track portions, a rod fixedly secured to said carriage and formed with a spirally extending groove, a tube beyond said rod and having its inner end telescopically 75 accommodating the outer end of the rod, a head at the outer end of said tube and means associated with said tube and extending into the spiral groove of said rod to assure a turning of said tube.
9. A lock including a casing formed with track portions, a carriage slidably mounted upon said track portions, a rod fixedly secured to said carriage and formed with a spirally extending groove, a tube beyond said rod and having its inner end telescopically 80 accommodating the outer end of the rod, a head at the outer end of said tube, said tracks having an interrupted portion, a projection forming a part of said tube and lying adjacent said track to ride into the interrupted portion thereof and permit a turning of said tube and means associated with said tube and extending into the spiral groove of said rod to assure a turning of the tube.
10. A lock including a casing formed with track portions, a carriage slidably mounted upon said track portions, a rod fixedly secured to said carriage and formed with a spirally extending groove, a tube beyond said rod and having its inner end telescopically 85 accommodating the outer end of the rod, a 125

head at the outer end of said tube, said tracks having an interrupted portion, a projection forming a part of said tube and lying adjacent said track to ride into the interrupted portion thereof and permit a turning of said tube, means associated with said tube and extending into the spiral groove of said rod to assure a turning of the tube, a dead-bolt encircling said tube and providing a mounting therefor and means for preventing an axial shifting of said tube with respect to said dead-bolt, said dead-bolt being projectable beyond said casing.

In testimony whereof I affix my signature.
